Attorney

UNITED STATES PATENT OFFICE.

SEXTUS A. EDDINS, OF BROCKTON, MASSACHUSETTS, ASSIGNOR TO CORDO-HYDE COMPANY, OF BROCKTON, MASSACHUSETTS, A CORPORATION OF MASSACHUSETTS.

PACKAGE FASTENER.

Application filed March 7, 1924. Serial No. 697,645.

To all whom it may concern:

Be it known that I, SEXTUS A. EDDINS, a citizen of the United States, and resident of Brockton, in the county of Plymouth and 5 State of Massachusetts, have invented an Improvement in Package Fasteners, of which the following description, in connection with the accompanying drawings, is a specification, like letters on the drawings 10 representing like parts.

My present invention is a novel and improved method of securing packages, boxes, bundles and the like, by means of a quick, automatically locking and retaining device.

Heretofore many efforts have been made 15 to provide a catch, clasp or the like permanently secured at one end of the cord or string in order to afford a convenient means for quickly wrapping, holding and securing 20 bundles, boxes, packages, etc., but none of these have proven entirely satisfactory. Most of such catches or clasps were objectionable, quickly wearing out, getting out of order, requiring difficult manipulation, and 25 constituting a serious obstruction, or objectionable as catching on other articles, etc. In my present invention I have obviated the difficulties above briefly outlined, having devised a form of automatic holding and locking 30 mechanism, which will itself, protect, conceal and guard the locked portion of the cord or string, presenting a smooth exterior surface, avoiding danger of catching or becoming unlocked, while at the same time 35 holding the cord firmly in locked position, permitting the cord to be drawn tightly, and hold the same securely when drawn up to the last degree of tension desired.

In carrying out my present invention I 40 provide a combined knot receiving and tensioning member, which consists in a circular or other suitably shaped resilient device, having a central dome or the like, and a peripheral flange. This may be of fibre, celluloid, rubber, metal or other compound, and with means therein to secure one end 45 of the attaching cord. Preferably I so position the cord that its leading portion will extend from the device adjacent the flange, said 50 flange being the tensioning member cooperating with the cord. This I accomplish by forming two holes in the dome portion of the device, threading the cord therethrough, knotting one end and leading the loose 55 end or bight of the cord outwardly adjacent

the flange and underneath the same. Thus when the device and cord are applied to a package and the free end of the cord wrapped around the device, interlocking with the secure end of the cord between 60 same and the tensioning flange, I secure at once a frictional tension and interlocking action. Several wrappings of the cord around the device increasing the tension and 65 interlocking. Where the cord has been applied around four sides of the rectangular article, I thus secure four interlocking engagements, each time the cord is wrapped around the device under the flange. Repeated interwrappings increase the securing 70 action. Furthermore, the construction, arrangement and combination of the member and the cord, prevent fraying, cutting or damaging the cord, while still exerting the desired tension thereon to secure the benefit 75 of the interlocking action above explained.

Other features, novel advantages and important characteristics of the invention will be hereinafter more fully pointed out and 80 claimed.

Referring to the drawings, illustrating a preferred embodiment of my invention,

Fig. 1 is a plan view showing my improved tying and holding device applied to 85 a rectangular package;

Fig. 2 is an enlarged view illustrating the interlocking feature;

Fig. 3 is a corresponding enlarged view showing a single turn of the interlocking 90 effect;

Fig. 4 is a cross-sectional view on the line 4-4 of Fig. 2; and

Fig. 5 is a cross-sectional view on the line 5-5 of Fig. 3.

It will be appreciated that my device 95 may consist in a member and cord, string or the like of any suitable size, strength, length and capacity. As illustrated in Fig. 1 I have shown same in substantially actual size for usual package, carton or bundle 100 use. As herein illustrated 1 designates a rectangular package, such for example as a bundle, box or other article which it is desired to secure by a string or cord. My improved device consists in the member 105 designated generally at 2 and the cord 3. The member 2 may be of metal, rubber, fiber or other suitable or desired equivalent material, preferably being tough and resilient, and comprises the dome shaped central portion 110

5 and a circular flange portion 6. This member is preferably circular, but may of course be of any other desired contour. The member is of sufficient strength to receive holes 7 and 8 through which the cord 3 is threaded and the knot 10 at one end of the cord 3 holds the same against displacement and is concealed and protected within the dome shaped section 5. With the 10 cord 3 thus threaded through from the interior of the dome 5 and with the knot therein, then inwardly through the recess 8—the latter adjacent the flange 6, the cord is then led around the article or package 15 to be secured. As herein shown for convenience, I have designated the parts of the cord 3 as the same is led from the opening 8 around the article 1, as 15 and 16, when a single encircling corded action is 20 desired, and 17 and 18 when a plurality, as shown in Figs. 1, 2 and 4 is desired, 20 indicated the free end of the cord in each instance.

In applying my device to an article 1, the 25 member 2 is placed approximately centrally and the free end of the cord wrapped around—as indicated at 15 and 16, Fig. 3—the free end 20 being rove around under the flange 6 and into interlocking engagement, as indicated at 21, Fig. 5, between that portion of the cord 3 as it emerges on the inside of the dome 5 and the adjacent flange 6, together with the first part 30 16. The binding action and tension of the interlocking parts as thus explained, and in cooperation with the tension of the flange 6 to hold the cords firmly, tightly and securely into the position to which they are tightened automatically and instantly. Additional turns can be taken if desired by the end 20 if of sufficient length, and the entire device can be loosened by a simple reversal of the tightening action, unwinding the loose end 20 in opposition to the

direction in which it has been wound. The 45 cord can be wound either from right to left or reverse and in either instance holds firmly and strongly, and automatically as shown. The cord and fastener can be used indefinitely and the flange 6 can, if desired, 50 be employed for advertising or other uses.

It will be noted that my improved device constitutes a quick-acting, positive locking device, readily unloosed and capable of repeated and continuous reusing. 55 The cord itself is wound and locked in a manner to preserve its strength and without sharp angles or the like which would tend to cut or weaken the same, thus insuring long usefulness. The dome-like form 60 the carrying and securing member furthermore conceals and protects the interlocking sections or portions of the cord, irrespective of size, and will hold same whether 65 the cord is wrapped around once or many times, this also preserving the smooth exterior over the knotted portions.

My invention is further described and defined in the form of claims as follows:

A package fastener, comprising a circular member having a dome shaped portion and an upwardly inclined flange formed integral therewith at its periphery, said dome shaped portion being provided with a plurality of perforations, and a cord having a knot at one end, the knotted end lying within the concavity of the dome, said cord passing upwardly through one of the holes and thence downwardly through the other hole, whereby, when the loose cord portion is wrapped about a bundle, the convolutions of the cord will be interlocked beneath the flange and with the portion of the cord adjacent the second of the holes in the dome shaped portion.

In testimony whereof, I have signed my name to this specification.

SEXTUS A. EDDINS.
